UNITED STATES PATENT OFFICE.

JOHN J. HALLIWELL, OF NEW YORK, N. Y., ASSIGNOR TO R. HOE AND CO., OF NEW YORK, N. Y., A CORPORATION OF NEW YORK.

INKING MECHANISM.

1,130,727.

Specification of Letters Patent.

Patented Mar. 9, 1915.

Application filed June 25, 1913. Serial No. 775,666.

To all whom it may concern.

Be it known that I, JOHN J. HALLIWELL, a citizen of the United States, residing at New York, county of New York, and State 5 of New York, have invented certain new and useful Improvements in Inking Mechanism, fully described and represented in the following specification and the accompanying drawings, forming a part of the same.

10 This invention relates to improvements in inking mechanism for printing machines, and particularly to the mechanism employed for driving the fountain roll of such mechanisms.

15 It is one object of the present invention to provide a driving mechanism for the fountain roll which shall comprise fewer parts than constructions heretofore employed for such purpose, which shall be 20 compact, and which shall give a smooth motion to the driven roll.

25 It is a further object of the invention to provide a construction in which the distributor rolls, when employed, and the connections for driving the fountain roll, may be operated from the same shaft.

30 For a full understanding of the invention, a description of a machine embodying the same will now be given in connection with the accompanying drawings, in which—

Figure 1 is a side elevation of the improved mechanism, shown in connection with a distributor cylinder and the distributor rolls of a rotary press; Fig. 2 is a plan 35 view, partly in section, of the construction shown in Fig. 1, and Fig. 3 is a detail view, with certain parts broken away to show the construction, taken on the line 3—3 of Fig. 1.

40 Referring now to the drawings, which illustrate one embodiment of the invention as used with a rotary machine, the form cylinder of the press is indicated at 1. The form cylinder is inked by the usual form 45 rollers 2 3 which take their ink from a distributing cylinder 4 of any usual or suitable construction. Machines of this type are usually provided with a number of distributing rolls which coöperate with the distributing cylinder 4 to even up the ink. In the particular construction illustrated, there 50 are three of these distributing rolls 5, 6 and 7, which are supported on shafts suitably journaled in the frame of the machine. 55 These rolls seat on, and are rotated by,

frictional contact with the distributing cylinder, and are preferably given a reciprocating movement longitudinally thereof to more evenly distribute the ink. As illustrated, the roll shafts beyond the rolls are 60 provided with grooved collars 8 into which take studs 9 on crank arms 10, 11 and 12. These crank arms are oscillated by a rock shaft 13 suitably journaled in the frame of the machine, this shaft being rocked through 65 an arm 14 having a slotted face 15 into which takes a stud 16 fast on a worm wheel 17, the stud being off center of the wheel. The worm wheel is fast on a shaft 18, and is driven in any suitable manner, as from a 70 worm 18' on the shaft of distributor cylinder 4.

Machines embodying the invention will include an ink fountain 19, of any suitable or desired construction, in which is mounted 75 to rotate a fountain roll 20, which is carried on a shaft 21 suitably journaled in the frame of the machine. This fountain roll is intermittently rotated through connections which are preferably actuated from the 80 shaft 18 before referred to, from which the distributor rolls 5, 6 and 7 are operated.

The connections for effecting intermittent rotation may be varied. In the particular construction illustrated, there is provided a 85 ratchet gear 22 fast on a short shaft 23 suitably journaled in the frame of the machine, this shaft 23 being arranged to be coupled to and uncoupled from roll shaft 21 as desired by any suitable coupling, as by split collar 24. 90 Cooperating with the ratchet 22 is a pawl 25 on a pawl-stud 26 fast on a pawl-arm 27, loose on the shaft 23 before referred to. The arm 27 is or may be held on the shaft by a collar 28 having holes 29 in which a suitable tool may 95 be inserted to turn the mechanism over by hand. The pawl-arm 27 is actuated to cause the pawl to intermittently turn the ratchet gear through connections from the shaft 18 before referred to, and these connections will, 100 in the best constructions, be such as to positively operate the arm in both directions. While the particular construction may be somewhat varied, as illustrated, the shaft 18 has fast thereon a cam 30 which has a hub 105 31. The hub 31 has a slotted outer face in which is mounted a stud 32, this stud being vertically adjustable in the slot through a set screw 33. Depending from the stud is a crank arm 34 which is provided at its lower 110

end with a hole 35. To avoid lost motion, an improved connection between the end of the crank arm 34 and the pawl 27 is provided. In the construction illustrated, the 5 hole 35 is round and is adapted to receive a ball 36 which carries a stud 37, the crank arm being of sufficient thickness at this point so that the center of the ball shall be within the arm. The stud 37 takes into a suitable 10 recess in arm 27 and thus throws the arm a distance depending on the position of stud 32 in hub 31, the throw of the arm 27 being positive in both directions. This construction is very simple and compact and return 15 springs for the arm are eliminated. The pawl arm 27 is furthermore, through the connections described, driven directly from the shaft 18 operating the distributor rolls, thus affording a simple construction, and, 20 through the ball connection to arm 34, lost motion is avoided and a smooth running mechanism produced.

In inking mechanisms of the type described, the ink is taken from the fountain 25 roll and delivered to the distributing cylinder by an oscillating ductor roll 40 which is operated in any suitable manner. In the particular construction illustrated, this ductor is oscillated from the cam 30 before re-

ferred to through a cam roll 41 and rock 30 arms 42, 43, on a rock shaft 44 suitably mounted in the frame of the machine. In the construction illustrated, the cam 30 lifts the ductor from the fountain roll against the distributing cylinder. The ductor, in 35 the construction illustrated, is returned to position by a spring rod construction 45 of usual design.

Changes and variations may be made in the specific construction shown and described, and it is understood that such changes may be made without departing from the invention.

What is claimed is:—

In an inking mechanism, the combination 45 with distributing cylinder 4 of horizontal shaft 18 driven therefrom, hub 31 on the shaft, crank 34 adjustably carried in the hub, pawl arm 27 and ball 36 connecting the crank and arm.

In testimony whereof, I have hereunto set my hand, in the presence of two subscribing witnesses.

JOHN J. HALLIWELL.
